UNITED STATES PATENT OFFICE.

GEORGE T. COOLEY, OF JOPLIN, MISSOURI.

CONCENTRATOR.

Application filed November 19, 1918. Serial No. 263,185.

To all whom it may concern:

Be it known that I, GEORGE T. COOLEY, a citizen of the United States of America, residing at Joplin, in the county of Jasper and State of Missouri, have invented certain new and useful Improvements in Concentrators, of which the following is a specification.

My invention relates to an improvement in concentrators and it comprises a double deck machine, the upper deck or table being a rougher and the lower one a finisher, there being means for conducting the concentrates from the lower end of the rougher to the feed end of the finisher.

My invention further consists in a rougher having pan riffles disposed in fan like form and extending throughout the length of the table and of gradually increasing height down the surface of the table.

My invention also comprises, in connection with the two decks or tables, a means for imparting a horizontal gyratory rotary motion to the feed end of one table and a smart bump to the feed end of the other table.

This invention likewise consists in tables which are thoroughly adjustable in all directions while the machine is in operation.

This invention further consists in certain novel features of construction and combination of parts which will be hereinafter described and pointed out in the claims.

In the accompanying drawings Figure 1, is a top plan view.

Figure 2, is a vertical section through a portion of the feed end of the machine.

Figure 3, is a perspective view of the head motion.

Figure 4, is a transverse section on line 4-4 of Fig. 1 through the upper or rougher table, and Fig. 5 is a detached view showing the connection at the rear of the frame and the tables.

A, represents the frame of the machine upon which the tables are supported.

Both tables are preferably alike in general dimensions and size, although this is not necessary.

The upper table 1, is a roughing table and its surface is partly riffled and the remaining portion is relatively smooth, as shown in Figure 1. The riffles 2, are preferably made of sheet metal, as shown in Figures 1 and 4, and they are graduated in height both lengthwise and down the slope of the

table, the uppermost riffle tapering from say $1\frac{1}{2}$ " in height to $1\frac{1}{16}$ " and the lowermost from 1" at the feed end to $1\frac{1}{4}$ " and these riffles extend from the feed end and gradually converge to the concentrates discharge end, where they are in consequence not only reduced in height but also in width and capacity. These riffles are preferably slightly curved or panned, as shown in Figure 4, and for this purpose a shim 5, is inserted therebeneath to give the required slope and curvature.

The numeral 6, indicates the feed box in which the ore pulp is fed and 7 is the usual water box for creating the side wash upon the sloping surface of the table.

The finishing table is indicated by the numeral 8, and is located below table 1, and may be of any of the well known types of so-called sand tables as, for instance, the Wilfley type, in which the riffles 9 are of uniform length at the head or feed end and terminate at the opposite end on a diagonal line of separation, leaving a relatively smooth surface 10.

The tables are supported in any approved manner but preferably at the discharge end by means of rods 11. These rods are slidably held by straps 12, on the sides of the frame and are screw-threaded at their upper ends where they are provided with hand wheels 13, which are easily turned in order to raise and lower the table at the discharge end and by means of which it is possible not only to adjust the transverse but also the longitudinal slope or inclination of the tables or decks.

The feed or head end of the upper table 1, is supported in any common manner but preferably by means of a dumb bell 14, as shown in Figure 2, which gives freedom for the gyratory reciprocating motion imparted to this upper table.

The numeral 15, shows the main drive shaft. This is horizontally located, as shown in Figures 1 and 2 and is provided with a belt pulley 16, at one end, over which the drive belt 17, passes and with a bevel gear 18, at the opposite end, the teeth of which mesh with the teeth of the bevel gear 19, on the upper end of the drive shaft 20. The drive shaft 20, is provided with the compound eccentric 21, and this is surrounded by an eccentric strap 22, which has extending therefrom and connected at its forward end to the table 1 by means of a bracket 24

received, between the two nuts 25, on the forward end of the rod 23, through this means the horizontal gyratory motion is imparted to the head end of the upper or 5 roughing table 1, thus giving it an impulse toward the lower or tailings discharge side of the table, while imparting a less violent or reciprocating motion at the opposite or concentrates discharge end, in this way separating 10 the gangue in the usual way from the concentrates, the heavier concentrates taking shelter beneath or in the curve or grooves of the riffles and being conveyed lengthwise or endwise therewith to the concentrates discharge launder 26, while the lighter gangue and waste is being floated off over the tops of the riffles down the slope of the table.

From the launder a trough 27, leads alongside the frame of the machine to the feed 20 end of the lower or finishing table 8, where it discharges and whereupon this richer ore is re-worked and finally cleaned and separated in the usual manner of handling a finishing table, such as a Wilfley or other 25 sand table of its general type.

While various kinds of head motions might be applied to the finishing table, I propose to adopt the bump variety and this is accomplished by the means of the rod 28, 30 which has a connection with the end of the table very much as described in connection with table 1, that is, the same parts 24 and 25 serving as a fastening means. To reduce friction to a minimum I employ ball bearings 29 and the forward end of this sliding rod is provided with an anti-friction wheel 30, in position to bear against and traverse the double helical edge of the double cam 31, which has the abrupt shoulders or drops 35 32 which the roller 30 on the end of the rod

28, follows and the springs 31^a are provided to cause the smart or sharp bump upon the shoulders 32 of the double cam. These springs 31^a, are pocketed in the recesses 32^a and there are preferably four of them to give the required stiffness and their outer ends bear 45 upon the collar 33 on the rod 28.

Motion is imparted through the belt 17 and transmitted to the vertical drive shaft 20 and there being two bumps upon the 50 double cam 31, just twice as many impulses are given to the lower or finishing table that are to the upper or roughing table.

With this double deck table combining both a rougher and finisher with pan riffles and means for universal adjustment while in operation, I have provided a table of very large capacity and efficiency and one in which the ore is successfully washed and dressed without the necessity of re-handling. 55 60

I claim:

The combination with a frame, of two tables adjustably supported at one end thereon, one having a fan-shaped arrangement of riffles which taper and converge lengthwise 65 of the table, and are of gradually decreasing height down the slope of the table, means at the discharge end for adjusting the tables while in operation, and a single head motion common to both tables comprising a 70 shaft having a horizontally disposed eccentric thereon, with means extending therefrom to one table, and provided with a double cam with abrupt shoulders, and a spring-actuated sliding rod connected with 75 the other table and adapted to be actuated thereby.

In testimony whereof I affix my signature.

GEORGE T. COOLEY.
